UNITED STATES PATENT OFFICE.

HENRY R. BEVIER, OF BATTLE CREEK, MICHIGAN, ASSIGNOR TO JOHNSON AUTOMATIC SEALER CO. LTD., OF BATTLE CREEK, MICHIGAN.

CARTON-SEALING MACHINE.

1,332,196.

Specification of Letters Patent.

Patented Mar. 2, 1920.

Application filed April 30, 1919. Serial No. 293,707.

To all whom it may concern:

Be it known that I, HENRY R. BEVIER, a citizen of the United States, residing at Battle Creek, county of Calhoun, State of Michigan, have invented certain new and useful Improvements in Carton-Sealing Machines, of which the following is a specification.

This invention relates to improvements in 10 carton sealing machines.

The main objects of this invention are:

First, to provide in a carton sealing machine an improved means for supporting the flaps to insure the even application of 15 glue thereto.

Second, to provide in a carton sealing machine an improved means for supporting carton flaps as they are acted upon by the glue rollers so that the cartons are not likely 20 to be distorted during the operation.

Third, to provide in a carton sealing machine an improved means for applying the glue to the flaps which is economical in the use of glue.

25 Further objects, and objects relating to structural details, will definitely appear from the detailed description to follow.

I accomplish the objects of my invention by the devices and means described in the 30 following specification. The invention is clearly defined and pointed out in the claims.

A structure which is a preferred embodiment of my invention is clearly illustrated 35 in the accompanying drawing, forming a part of this specification, in which:

Figure I is a detail view partially in transverse section looking from the left of 40 Fig. II of a carton sealing machine embodying the features of my invention, certain parts of the machine not forming a part of my invention being omitted and other parts being shown mainly in conventional form.

Fig. II is a detail vertical longitudinal 45 section on a line corresponding to line 2—2 of Fig. I.

Fig. III is a detail longitudinal section on a line corresponding to line 3—3 of Fig. I, showing details of the flap supporting 50 means.

Fig. IV is a detail view partially in section on a line corresponding to line 4—4 of Fig. III, showing details of the control means.

Fig. V is a detail section on a line corresponding to line 5—5 of Fig. I.

Fig. VI is a detail view partially in section on a line corresponding to line 6—6 of Figs. I and II, showing details of the control means.

In the drawing similar reference characters refer to similar parts throughout the several views, and the sectional views are taken looking in the direction of the little arrows at the ends of the section lines.

In the accompanying drawing I have illustrated only such parts of a sealing machine as seem desirable to illustrate an adaptation of my improvements and other parts are shown conventionally.

The supporting frame is designated generally by the numeral 1. The feed conveyer 2 is provided with flight-like holders 3 for the cartons 4, the machine illustrated being a bottom sealing machine. As the cartons 75 4 are carried into the machine their rear flaps are folded forwardly by the oscillating flap folder 5 mounted on the shaft 6 above the conveyer. The front flap is folded downwardly upon the folded rear flap by 80 the cartons passing under the flap folder and spreader 7. This front flap folder and flap spreader is designed to fold the front flap upon the previously folded rear flap and spread the side flaps 8 of the carton 4 85 outwardly. At the rear of this flap spreader are glue wheels 9 which receive their glue from the troughs 10. The glue wheels are driven from the shaft 11 having a driving pulley 12 thereon, the shaft being connected 90 by the gears 13 and 14 to the glue rollers.

The flap spreader has a rearward plate-like extension 15 and while still retained in their spread position the flaps are engaged by the flap supporting and pressing plates 95 16 carried by the chains 17. These chains are supported by the sprockets 18 and 19, the sprockets 19 being the driving sprockets and carried by shafts 20. These shafts are supported by brackets 21 projecting inwardly from the frame so that the cartons may pass between as shown in Fig. I. As the flaps 8 supported by the plates 16 pass from the retaining members 15 they travel under the glue rollers 9.

To support the upper reaches of the chain 17 and yieldingly press the flaps against the glue rollers I provide the bars 22 which are

disposed between the sprockets to support the upper reaches of the chains, as shown in Fig. II. These bars are yieldingly supported by springs 23 and the pins 24 carried by arms 25 projecting from the supporting brackets for the sprocket wheel shaft.

The shafts 20 are connected to the jack shaft 26 by means of sprockets 27 thereon 10 and sprockets 28 on the shafts 20 and the sprocket chains 29. The jack shaft 26 has a driving clutch member 30 rotatably mounted thereon and driven from the chain 31 and a coacting driven clutch member 32 keyed to the shaft.

The driven clutch member carries a spring actuated engaging member 33 which projects therefrom in position to be engaged by the releasing member 34 carried by the pivot shaft 35 which is shown in Fig. I in its retracted position. The clutch engaging member is actuated by spring 36 so that normally the clutch is engaged. When, however, the releasing member 34 is in its normal or 25 clutch releasing position the clutch engaging member 33 comes into contact therewith as the clutch rotates thereby releasing the clutch. The releasing member is actuated from the rock shaft 37 having a trip arm 38 30 thereon adapted to be engaged by the cartons as they are carried along by the feed conveyer which actuates the releasing member so that the clutch engaging member passes on each revolution of the clutch providing a continuous drive for the jack shaft until a holder having no carton thereon 35 passes the arm when the clutch is released until the rock shaft is again actuated to actuate the releasing member.

40 The holders have notch-like recesses 39 to permit their passing the arm 38 without actuating the same when no carton is present. The rock shaft 37 is provided with an arm 40 connected to the release member 34 by the link 41. A spring 42 connected with the arm 40 and to the frame returns the release member to its releasing position.

With the parts thus arranged the flaps to 50 be glued are firmly pressed against the glue rollers at the same time their supports traveling with the conveyer prevent their being distorted or twisted on account of such pressure. By thus supporting and pressing them against the glue rollers a thinner glue and a less quantity of glue is sufficient to properly secure the desired adhesiveness than is necessary otherwise, so that my improvements result in a saving of glue and, further, 55 the thin small quantity of glue sets quickly. By driving the flap supporting means only when cartons are present, the supporting plates pass the glue rollers only when protected by the flaps so that they do not become fouled with the glue which would seri-

ously interfere with the practical operation of the machine.

I have not shown means for closing and sealing the flaps after the glue is applied thereto as such means form no part of this 70 invention. I have not attempted to illustrate or describe various adaptations and modifications which I contemplate as I believe the disclosure made will enable those skilled in the art to which my invention relates to embody or adapt the same as may be desired. 75

Having thus described my invention, what I claim as new and desire to secure by Letters Patent, is:

80 1. In a carton sealing machine, the combination with a feed conveyer provided with carton holders, glue rollers disposed above said feed conveyer, flap spreaders disposed in front of said glue rollers, flap supporting means comprising sprocket chains and driving and supporting sprockets therefor, disposed so that the upper reaches of the chains are supported in a horizontal position below the glue rollers, flap supporting plates 90 mounted on said chains to engage the under sides of the flaps while below said spreaders and travel therewith as the cartons are carried along by the feed conveyer to the glue rollers, yielding supporting bars for the 95 upper reaches of said chains disposed between their sprockets so that the flaps are pressed against the glue rollers as they travel past them, a jack shaft disposed below said feed conveyer, driving connections for 100 said jack shaft to the driving sprockets of said flap supporting means, a driving clutch member rotatably mounted on said jack shaft, a coacting driven clutch member keyed to said shaft, a spring actuated engaging member for said clutch members carried by said driven clutch members, a releasing member normally in position to release said engaging member, and a rock shaft connected to said releasing member and provided with a trip arm disposed to be engaged by cartons carried by said carton holders and operatively connected to said clutch releasing member so that when said carton holders have cartons thereon 115 said clutch is actuated to drive said flap supporting means, the carton holders being recessed to receive said trip arm so that it is actuated only when the holders are carrying cartons. 120

125 2. In a carton sealing machine, the combination with a feed conveyer provided with carton holders, glue rollers disposed above said feed conveyer, flap spreaders disposed in front of said glue rollers, flap supporting means comprising sprocket chains and driving and supporting sprockets therefor, disposed so that the upper reaches of the chains are supported in a horizontal position below the glue rollers, flap supporting plates 130

said feed conveyer, flap spreaders disposed in front of said glue rollers, flap supporting and pressing means comprising sprocket chains and driving and supporting sprockets 5 therefor, disposed so that the upper reaches of the chains are supported in a horizontal position below the glue rollers, flap supporting plates mounted on said chains to engage the under sides of the flaps and travel therewith as the cartons are carried along by the feed conveyer, yielding supporting bars for the upper reaches of said chains disposed between their sprockets so that the flaps are yieldingly pressed against the glue rollers 10 as they travel past them, and a jack shaft disposed below said feed conveyer.

8. In a carton sealing machine, the combination with a feed conveyer provided with carton holders, a glue roller, flap supporting 20 and pressing means comprising a sprocket chain and driving and supporting sprockets therefor, flap supporting plates mounted on said chain to engage the flaps and travel therewith as the cartons are carried along by the feed conveyer, a yielding supporting bar for the upper reach of said chain disposed between its sprocket so that the flaps are yieldingly pressed against the glue roller as they travel past it, a driving means for 25 said flap supporting and pressing means comprising a clutch, a releasing member normally in position to release said engaging member, and a rock shaft connected to said releasing member and provided with a trip 30 arm disposed to be engaged by cartons carried by said carton holders and operatively connected to said clutch releasing member so that when said carton holders have cartons thereon said clutch is actuated to drive 35 said flap supporting means.

9. In a carton sealing machine, the combination with a feed conveyer provided with carton holders, a glue roller, flap supporting 45 and pressing means comprising a sprocket chain and driving and supporting sprockets therefor, flap supporting plates mounted on said chain to engage the flaps and travel therewith as the cartons are carried along by the feed conveyer, a driving means for 50 said flap supporting and pressing means comprising a clutch, a releasing member normally in position to release said engaging member, and a rock shaft connected to said releasing member and provided with a trip 55 arm disposed to be engaged by cartons car-

ried by said carton holders and operatively connected to said clutch releasing member so that when said carton holders have cartons thereon said clutch is actuated to drive said flap supporting means.

60

10. In a carton sealing machine, the combination with a feed conveyer provided with carton holders, a glue roller, flap supporting and pressing means comprising a sprocket chain and driving and supporting sprockets 65 therefor, flap supporting plates mounted on said chain to engage the flaps and travel therewith as the cartons are carried along by the feed conveyer, a yielding supporting bar for the upper reach of said chain disposed between its sprocket so that the flaps are yieldingly pressed against the glue roller as they travel past it, and a driving means for 70 said flap supporting and pressing means.

70

11. In a carton sealing machine, the combination with a feed conveyer, a glue roller, a traveling flap supporting and pressing means comprising flap supporting plates adapted to engage the flaps and travel therewith as the cartons are carried along by the 80 feed conveyer, said supporting plates being held yieldingly toward the glue roller so that the flaps are supported and pressed against the glue roller as they travel past it, a driving means for said flap support and 85 pressing means including a clutch, and a control means for said clutch actuated by the cartons on the conveyer so that said flap supporting and pressing means is driven only when the feed conveyer is carrying cartons and the flap supporting plates prevented from contacting with the glue roller 90 by the carton flaps.

90

12. In a carton sealing machine, the combination with a feed conveyer, a glue roller, 95 and a traveling flap supporting and pressing means comprising flap supporting plates adapted to engage the flaps and travel therewith as the cartons are carried along by the feed conveyer, said supporting plates being 100 held yieldingly toward the glue roller so that the flaps are supported and pressed against the glue roller as they travel past it.

100

In witness whereof, I have hereunto set my hand and seal in the presence of two 105 witnesses.
